UNITED STATES PATENT OFFICE

WILLIAM E. WINE, OF TOLEDO, OHIO.

CAR-DOOR MECHANISM.

Application filed April 17, 1922. Serial No. 552,602.

To all whom it may concern:

Be it known that I, WILLIAM E. WINE, a citizen of the United States, residing at Toledo, in the county of Lucas and State 5 of Ohio, have invented certain new and useful Improvements in Car-Door Mechanisms, of which the following is a specification.

This invention relates to a door arrangement for railway cars, and has among its 10 objects to provide an improved form of door device, wherein a swinging door may be lifted and caused to seat upon supporting ledges formed upon the car body and be held in position upon such ledges in a simple and 15 efficient manner. Another object of the invention is to provide in combination with a railway car, a door arranged for swinging motion, and arranged also for a slipping motion in addition to the swinging motion, and 20 in connection therewith a supporting device affixed to the car body and arranged to support the door in closed position, the door being engageable and disengageable with the supporting means through the aforesaid 25 slipping motion.

Other objects are to provide a simple and substantial form of door securing and retaining mechanism in combination with a movable car door, also to produce a door device 30 of low cost and sturdy construction.

With these and other more specific objects in view, the invention consists of the formation, combination and arrangement of parts as will be herein described and particularly pointed out in the appended claims.

In the accompanying drawings, which show a preferred embodiment of the invention, Figure 1 is a fragmentary plan view, showing a portion of the floor of a car, in 40 which is shown a swinging door and a supporting mechanism therefor, all being constructed in accordance with the principles of the present invention.

Figure 2 is a fragmentary transverse vertical section through a portion of the same, this figure being taken approximately on the line 2-2 of Figure 1. Figure 3 is a view similar to Figure 2, taken on the line 3-3 of Figure 1. Figure 4 is a fragmentary side 50 elevational view of the car body, showing a door in closed position. Figure 5 is an enlarged view of the ledges which are formed upon the car body, and upon one of which a portion of the door seats when the door is 55 in closed position. This view is in vertical section and is taken approximately on the

line 5-5 of Figure 3. Figure 6 is a transverse vertical sectional view taken through a portion of the door supporting mechanism, this view being taken on the line 6-6 of 60 Figure 5.

Referring to these drawings, the car body, which may be of the customary type, is shown as arranged with a side plate 1 and the usual side stakes 2. Along the lower 65 edge of the side of the car is shown a bottom reinforcing member, such as the channel 4. The side 1 of the car may be composed of suitably arranged planks such as 5, or in any other manner desired. At 6 is indicated one 70 of the channel irons which comprise the customary center sill of the car. A center sill facing plank, such as 7, may be used to protect the channel and define the lading cavity of the car. 75

Attached to the outer face of the channel 6 are door hinges 8, these hinges having aligned pintle openings, which are arranged to receive and accommodate a pintle rod 9. This rod extends longitudinally of the car 80 and along the outer face of the center sill channel 6. A door, indicated at 10, is arranged for swinging motion with respect to the pintle rod 9, the door being in the present embodiment arranged to swing transversely 85 of the car and extending from beneath the plank 7 to beneath one of the side planks 5. A suitable opening is arranged in the floor 11 of the car, and the door 10 is arranged to seat beneath this opening in order to close 90 the same against loss of lading.

The door 10 may be made up of a series of door planks 12. These are shown in the present embodiment as secured to angle iron stiffening members 13 which underlie the planks 95 12, and to which angles the planks are secured by means of bolts such as 14. These angle irons 13 extend transversely of the car and the outer ends of the angles are carried out as at 15 to slightly outside of the lines of 100 the car side, and these form locking arms or brackets which may be positioned upon suitable supporting ledges formed on the car body.

The angle irons 13 are spaced somewhat 105 with respect to each other, and hinge members 16 are bolted to the angle irons, these hinge members being arranged for swinging co-operation with the pintle rod 9. The rod 9 extends through these hinge members 16, 110 and suitable retaining means such as cotter pins 17 may be inserted through the ends

of the rod 9 to prevent its dislocation. It will be noted that the pintle openings 18 of the hinge members 16 are somewhat elongated, so as to allow some slippage of the door with respect to the rod 9. As the rod 9 is held in reasonably fixed relationship with the car body by means of the hinge members 8, it will be seen that the door 10 is capable, through the clearance of the 10 pintle openings 18 in the hinge members 16, of a slight slippage with respect to the car body.

A third hinge member 19 is also bolted to the car door and the pintle rod 9 extends 15 through an opening 20 in this hinge member. The hinge member 19 is located approximately midway between the hinge members 16, and the eye 20 thereof is arranged to allow a pivotal movement of the door with 20 respect to the rod 9. A point 21 has been indicated in Figure 1 to denote the approximate upright axis about which, as a center of rotation, the door may be shifted or slipped, when desired, the clearance of the 25 eyes 18 of the hinge member 16 permitting this slipping movement. At the same time the entire door may be swung downward in the customary manner about the hinge pintle 9. This slippage of the door is utilized, 30 as will shortly be explained, to position the door upon the supporting ledges 24, or to release it therefrom.

Referring particularly to Figure 4, the car is shown as supplied with two brackets 35 22 which are affixed to the side of the car in a rigid manner by means of the rivets 23. These brackets are located adjacent the outer ends 15 of the angle irons 13, and each of the brackets 22 is provided with a ledge 40 24 upon which the flat leg of the respective angle iron 15 may be seated when the door is closed. The angle irons are turned in the same direction and the ledges 24 of each bracket 22 are also turned in uniform directions, so that when the outer edge of the 45 door is lifted, causing the door to swing in the customary manner about the hinge pintle 9, the door may be, through the hinge action heretofore described, shifted in to the right, (see Figure 4), in such manner as 50 to position both of the angles 13 simultaneously upon their respective ledges 24. To release the door when it is desired to drop the same, the outer edge of the door is 55 shifted to the left, (Figure 4,) until the ends 15 of the angles 13 are clear of the ledges 24, when the door will drop by gravity. The door is shown in dotted lines in Figure 1 as shifted to the left, out of engagement with the ledges 24.

In order to prevent undesired release of the doors, hooks 25 are pivoted at 26 upon the brackets 22. These hooks are arranged to drop in position behind the angles 13 when 60 the latter are in position upon the ledges 24,

thereby interlocking the door and the brackets 22. When the hooks are so positioned it is not possible to shift the door laterally to permit the angles to drop off the ledges 24. When it is desired to release 70 the door, the hooks 25 may be swung upward, after which the door may be shifted as before described. The hooks 25 thus serve with the brackets 22 to hold the free edge of the door against undesired slippage 75 along the car and the hinges 8 are arranged to contact the hinges 16 to hold the hinged edge of the door against such slippage, the fit of the central hinge 19 over the pintle rod 9 being such as to allow of the rotative 80 movement desired.

It is often desired to close doors of this character by hand and without the employment of elaborate winding mechanisms. The brackets 22 may accordingly be arranged 85 with preliminary supporting ledges, such as 27, upon which the doors may be temporarily positioned after being lifted nearly shut by hand. It is not difficult to close such doors to this preliminary position, but 90 it often requires considerable force to fully close the door into position shown in Figure 4. To effect this final closing, a bracket 28 may be secured to the side of the car body as by means of the rivets 29. This bracket 95 is shown as provided with an opening 30 which faces toward the adjacent edge of the door, the door edge being defined in the present embodiment by the channel iron 31, which extends along the full face of the 100 door and is secured to each of the angles 13. The channel 31 thus serves as a stiffening member, and also protects the edge of the door against damage. An open hole 32 is provided in this channel 31, this hole facing towards and being approximately on line with the hole 30 in the bracket 28. A bar or rod may be inserted through the hole 30 so that the end of the bar extends within the hole 32, and by using this bar as 105 a pry, the door may be forced from its preliminary position on the ledges 27 to a final position on the ledges 24. The holes 30 and 32, together with the bar, may also be utilized to forcibly slip the door transversely 110 as is necessary for positioning the angles upon the supporting ledges, and also for shifting off these ledges when it is desired to release the doors.

I have thus described an embodiment of 115 the present invention. Other embodiments are contemplated within the scope of the appended claims without departing from the spirit of the invention.

What is claimed is:

1. In a door mechanism for railway cars, a door hinged to the car body, the hinges therefor being arranged to permit a slight rotative motion of the door about an axis normal to the plane of the door when in 120

closed position, the hinge members being also arranged to prevent longitudinal movement of the hinged edge of the door along the hinge pintles thereof except through the 5 rotative motion aforesaid, and door-supporting means, the same being engageable or disengageable with the door through the rotative movement aforesaid.

2. In a door mechanism for railway cars, 10 a door hinged to the car body, the hinges therefor being arranged to permit a slight rotative motion of the door about an axis normal to the plane of the door when in closed position, the hinge members being 15 also arranged to prevent longitudinal movement of the hinged edge of the door along the hinge pintles thereof except through the rotative motion aforesaid, and door-supporting means, the same being engageable 20 or disengageable with the door through the

rotative movement aforesaid, and means near the free edge of the door for locking the door against the said rotative motion.

3. In a door mechanism for railway cars, a door hinged to the car body in such manner as to be capable of normal swinging motion about the hinge pintles and of an additional slippage of the free edge of the door within the plane of the door, a door 25 securing hook rigidly affixed to the car body near the free edge of the door, a member affixed to the door and arranged to seat upon the said hook, when the free edge of the door is shifted as aforesaid, and a lock pivoted upon the said hook and arranged to 30 hold the door against such shifting.

In testimony whereof I affix my signature.

WILLIAM E. WINE.
